UNITED STATES PATENT OFFICE

2,229,037

APPARATUS FOR DISCHARGING THE CONTENTS OF HOPPERS AND THE LIKE

Thomas L. Boldman, Parma Heights, Ohio, assignor to The W. S. Tyler Company, Cleveland, Ohio, a corporation of Ohio

Application February 14, 1940, Serial No. 318,841

1 Claim. (Cl. 259—72)

This invention relates, as indicated, to an apparatus for discharging the contents of hoppers and the like, but has reference more particularly to an apparatus for discharging the contents of railroad hopper cars of the type generally used for transporting dry bulk commodities, such, for example, as cement and grain.

The gravity discharge of bulk commodities from railroad hopper cars is in most cases a relatively simple matter, but certain types of bulk commodities have a tendency to adhere to the sides of the hoppers, being dislodged therefrom only after considerable difficulty, involving at times the tapping of the sides of the hopper with a hammer or other tool or actual entry into the hopper for the purpose of removing materials of an especially adherent nature. These methods may entail injury or damage to the cars or hoppers as well as extra labor and are therefore objectionable.

A primary object of the present invention, accordingly, is to provide an apparatus for discharging the contents of such hoppers in such a manner as to clear the hoppers of any adhering materials, and without injury to the hoppers or the necessity of entering the hopper for such purpose.

Another object of the invention is to provide apparatus of the character described which can be readily attached to and removed from the hoppers without requirement of special tools or devices for this purpose.

A further object of the invention is to provide a bracket of special construction which may be permanently or removably secured to the hoppers and through the use of which the attachment and removal of the apparatus is greatly facilitated.

To the accomplishment of the foregoing and related ends, said invention, then, consists of the means hereinafter fully described and particularly pointed out in the claim, the annexed drawing and the following description setting forth in detail certain means and one mode of carrying out the invention, such disclosed means and mode illustrating, however, but several of various ways in which the principle of the invention may be used.

In said annexed drawing:

50 Fig. 1 is a side elevation of a railroad hopper car, showing the apparatus comprising the present invention as applied to the hoppers of such car;

55 Fig. 2 is a fragmentary elevational view of the

apparatus, as viewed in the direction indicated by the arrow A in Fig. 1;

Fig. 3 is an enlarged side elevational view of the apparatus shown in Fig. 2;

Fig. 4 is a fragmentary elevational view of the 5 apparatus, as viewed in the direction indicated by the arrow B in Fig. 1;

Fig. 5 is an enlarged side elevational view of the apparatus shown in Fig. 4;

Fig. 6 is a fragmentary perspective view showing the bracket for mounting the apparatus shown in Figs. 4 and 5;

Fig. 7 is a top plan view of the bracket;

Fig. 8 is a vertical cross-sectional view of the bracket, taken on the line 8—8 of Fig. 7; and 15

Fig. 9 is a fragmentary side elevational view of the male supporting member of the apparatus.

Referring now to the drawing, there is illustrated in Fig. 1 a railroad hopper 1 of conventional construction, and provided with the usual 20 reinforced "pant-leg" hoppers 2. Each hopper is provided with sloping end walls 3 and 4 and sloping side walls 5, and has a generally rectangular opening in the bottom thereof, which is normally closed as by a slidable gate 6. 25

Secured to each of the end walls 3 at a point centrally thereof, as by welding or bolting thereto, is a supporting bracket 7, the detailed construction of which is shown in Figs. 6, 7 and 8. Each bracket consists of a plate 8, and spaced L 30 flanges 9 extending from the inner face of the plate, these flanges forming a T shaped slot or recess 10. The inner surfaces 11 of those portions of the flanges which are spaced from the plate 8 are inclined with respect to the inner surface of the plate, so that the cross-section of the slot 10 is of gradually diminishing width from top to bottom of the bracket. The flanges 9 are reinforced by means of web portions 12 of the bracket, and the plates 8 are suitably apertured as at 13 for the reception of bolts 14, whereby the brackets may be removably secured to the hoppers. 35

Supporting brackets similar to those secured to the end walls 3 are also provided for the end walls 4, but are preferably secured to such walls at a level considerably lower than the point of securement of the brackets for the walls 3. Since hoppers, of this type, are usually recessed as at C (see Fig. 4) in their lower portion, it is necessary, in order to secure the brackets centrally of the walls 4, to provide a supporting member for the bracket, which member spans the recess C. In this case, such supporting member is in the form of a channel 15, which is secured at its ends, 50

55

as by welding or bolting, to the wall 4, the web of the channel providing a supporting surface for the bracket 7, as clearly shown in Figs. 4 and 5.

5 The brackets 7 are adapted for the support of devices for vibrating the walls of the hoppers to which they are secured. Such devices are preferably in the form of electromagnetic vibrators 16, such, for example, as disclosed in Reynolds Patent No. 1,852,677 and Delameter Patent No. 2,077,678, or, if desired, any conventional type of electromagnetic vibrator may be employed. To facilitate removably securing them to the bracket, such electromagnetic vibrators are modified to 10 the extent that they are provided with a casting 17, provided with a tenon 18 of T shaped cross-section, corresponding generally with the shape of the slot 10 in the bracket. The cross-member 19 of the tenon has rear walls 20 which are 15 inclined relatively to the front wall 21 of the cross-member, thereby providing spaced wedge-like members which wedgingly engage the walls of the slot 10 in the bracket.

20 The use of the apparatus will be readily understood from the following procedural description:

25 If the hopper car is equipped with brackets 7, electromagnetic vibrators of the type described are mounted on the brackets when the car arrives at its destination or point of unloading. The 30 gates 6 are then opened, and the hoppers permitted to discharge their contents. In the meantime the vibrators are energized by a suitable current supply, and, due to the fact that they vibrate about 1800 times per minute and impart such 35 vibrations directly to the hopper walls, will quickly clear the hoppers of any material which would, in the absence of the vibrators, tend to adhere to the hopper walls or accumulate in pockets or corners of the hoppers. Due to the wedge-like engagement of the cross-member 19 of the tenons 18 40 with the brackets 7, the vibrators, instead of becoming dislodged from the brackets as a result of the vibrations, will actually tend to become more tightly wedged thereto. The castings 17, in fact, become so tightly wedged in the brackets, 45

as to bar removal by ordinary means, and when it is desired to remove the vibrators, this must be done while they are energized, so that the vibrations will assist in their removal.

5 If the hopper car is not equipped with brackets, such brackets are secured to the hoppers when the car arrives at its destination.

A particular advantage resulting from the use of vibrators which are readily mountable and demountable is that it is unnecessary to carry the vibrators on the train. If the vibrators are carried on the train or mounted on the cars while in transit, they are not in use, and their usefulness is thus limited to only such periods when the cars are being unloaded. On the other hand, by having the vibrators readily mountable and demountable, a supply of vibrators may be carried at each unloading station, and such vibrators used more or less continuously, as the occasion for such use arises.

20 Further, the element of dead weight is eliminated, and the chances for stealing the vibrators from the cars are reduced.

25 Other modes of applying the principle of my invention may be employed instead of the one explained, change being made as regards the means and the steps herein disclosed, provided those stated by the following claim or its equivalent be employed.

30 I therefore particularly point out and distinctly claim as my invention:

35 In combination with a railroad hopper car having a hopper with integral inclined side and end wall portions, the lower portion of the walls of which are recessed and thereby provide spaced inclined portions of the same wall, a supporting member extending across said recess and secured to said spaced inclined wall portions, a bracket 40 removably secured to said supporting member centrally of said wall portions and having a recess therein, and a vibrator for vibrating said wall portions, said vibrator having thereon a tenon removably engaging in said recess to secure the vibrator to the hopper wall.

45 THOMAS L. BOLDMAN.
